(57) **ABSTRACT**

Surgical gowns can be configured to be worn by a human and to be sterile for use in a sterile surgical environment. Such a sterile surgical gown can include one or more pockets attached to the gown and configured to store surgical instruments. The sterile surgical gown can also include one or more rings attached to the gown and configured to hold surgical instruments. In some embodiments, a patch that is attachable to the gown. The patch can include one or more additional pockets or additional rings.

SURGICAL GOWNS

CROSS-REFERENCE TO RELATED APPLICATIONS

This application claims priority to U.S. application Ser. No. 17/056,581 filed on Nov. 18, 2020, (issued as U.S. Pat. No. 11,857,002), which is a National Stage application under 35 U.S.C. § 371 of International Application No. PCT/US2019/034570 having an International Filing Date of May 30, 2019, which claims priority to U.S. Application Ser. No. 62/677,843 filed on May 30, 2018. The disclosure of the prior applications are considered part of the disclosure of this application, and are incorporated in their entireties into this application.

BACKGROUND

1. Technical Field

This document relates to improved designs of surgical gowns.

2. Background Information

During surgery, the Certified Scrub Technician (CST) is generally focused on the needs of the Primary Surgeon (“Surgeon”), and is busy passing instruments to the Surgeon. The needs of the “Assistants” (Assistant Surgeon/Resident/Certified Surgical Assistant) on the other side of the surgical table are legitimate but sometimes can be a distraction from the CST’s point of view. From the Assistant’s point of view, any delay in getting the necessary instruments can sometimes be frustrating and hinder the smooth running of the procedure.

SUMMARY

This document describes improved designs of surgical gowns.

In one implementation, this disclosure is directed to a surgical gown configured to be worn by a human and to be sterile for use in a sterile surgical environment. Such a sterile surgical gown can include one or more pockets attached to the gown and configured to store surgical instruments. The sterile surgical gown can also include one or more rings attached to the gown and configured to hold surgical instruments. In some embodiments, a patch that is attachable to the gown. The patch can include one or more additional pockets or additional rings.

Particular embodiments of the subject matter described in this document can be implemented to realize one or more of the following advantages. In some embodiments, the surgical gowns described herein include pockets that can conveniently contain basic instruments such as scissors and forceps. These pockets can be located at different locations and varying angles to facilitate optimal access and thereby greatly obviate the need for almost 30-80% of the back and forth moves that occur between an Assistant and the CST.

Unless otherwise defined, all technical and scientific terms used herein have the same meaning as commonly understood by one of ordinary skill in the art to which this invention pertains. Although methods and materials similar or equivalent to those described herein can be used to practice the invention, suitable methods and materials are described herein. All publications, patent applications, patents, and other references mentioned herein are incorporated

2

by reference in their entirety. In case of conflict, the present specification, including definitions, will control. In addition, the materials, methods, and examples are illustrative only and not intended to be limiting.

5 The details of one or more embodiments of the invention are set forth in the accompanying drawings and the description herein. Other features, objects, and advantages of the invention will be apparent from the description and drawings, and from the claims.

DESCRIPTION OF THE DRAWINGS

FIG. 1 is a schematic diagram of a clinician wearing an example surgical gown in accordance with some embodiments.

15 Like reference numbers represent corresponding parts throughout.

DETAILED DESCRIPTION

20 This document describes improved designs of surgical gowns.

A surgical gown **100** with some “pockets” as anchors 25 (such as exemplified in FIG. 1), could provide literally a storage area that could provide the Assistants rapid access to their needs (forceps/scissors or such small items) and greatly obviate the need for almost 30-80% of the back and forth moves that occur between an Assistant and the CST. The inventors believe this would greatly improve the efficiency 30 during a surgical procedure.

35 The inventive concepts and designs of the surgical gowns described herein may also have broader applicability in other areas of clinical and laboratory medicine as well as other industries beyond medicine—where convenience and improved efficiency are worthy and desired goals.

40 Referring to FIG. 1, the example surgical gown **100** can include one or more holsters, rings, and/or belt loops (collectively referred henceforth as “loops **110**”) and one or 45 more pockets **120**. In some embodiments, the loops **110** and/or the pockets **120** are both made of flexible material such as fabric.

The loops **110** and/or the pockets **120** are designed to hold 45 instruments such as forceps/pickups and scissors or other simple, narrow instruments (the “instruments”). In some embodiments, these surgical gowns **100** are disposable—unlike the cloth gowns. In some embodiments, the gowns **100** can be reusable.

The size (width and length), position and angle of the 50 pockets **120** and/or loops **110** can be selected as needed for optimal access, ease and sterility.

The loops **110** are somewhat similar in configuration as those on trousers that hold belts (belt loops). These can be in place of the pockets **120**, or supplement the pockets **120** 55 as additional guides and anchors for the instruments. The loops **110** can be made in various sizes. A single gown **100** can have loops **110** of various sizes. In some embodiments, the loops **110** are made of an elastic. In some embodiments, two or more loops **110** are arranged in alignment with each other so that a single instrument will be held by the two or more aligned loops **110**.

60 In some embodiments, the pockets **120** can be free-standing by themselves or be supplemented with the loops **110**, as mentioned above—or in various combinations. The 65 goals of the pockets **120** and loops **110** are to hold the instruments and to promote easy and rapid access to the instruments for the surgeon and surgical assistants. This can

greatly promote the surgical efficiency at multiple levels during a procedure for the entire surgical team.

The instruments are secured in a stable fashion, e.g., to prevent “floating” of the instruments in situations such as a leaning position. The tips of the instruments are kept protected as much as possible. Sterility is also safe-guarded. In some embodiments, the open tops of the pockets 120 can have a closure, such as a hook and loop closure, an elastic band, or a purse string.

The pockets 120 can be located at various locations on the gown 100. For example, one or more pockets can be located on the sleeves (above and/or below the elbow), bodice (upper torso area), sides, and/or legs of the gown 100.

The pockets 120 can have various shapes. The gown 100 can have pockets 120 with various shapes. Alternatively, in some embodiments all of the pockets 120 have the same shape on a gown 100. In some embodiments, one or more of the pockets 120 can be specifically shaped to contain a particular type of instrument. In some embodiments, the pocket 120 can comprise a mesh material, transparent material, and/or elastic material.

The pockets 120 and/or loops 110 can be attached directly on the gown 100 when the gown 100 is manufactured. Alternatively, or additionally, in some embodiments a separate patch 130 of fabric that includes one or more loops 110 and/or one or more pockets 120 can be attached to the gown 100 after the manufacturing of the gown 100. Such a separate, attachable patch 130 could be made in various shapes such as, but not limited to, square, rectangular, circular, and elliptical. An attachable patch 130 can be delivered together with the gown 100 as a system, or purchased/available separately from the gown 100.

The base material of the attachable patch 130 can have an adhesive back that could then be attached onto the gown 100 “on demand” in the O.R. as needed. As an alternative to adhesive attachment, in some embodiments the attachable patch 130 can be attached to the gown 100 using hook and loop fastener(s), zipper(s), ties, and the like, and combinations thereof. In some embodiments, the attachable patch 130 can come pre-secured and sealed to the gown 100 during manufacturing for greater weight-bearing security.

While this specification contains many specific implementation details, these should not be construed as limitations on the scope of any invention or of what may be claimed, but rather as descriptions of features that may be specific to particular embodiments of particular inventions. Certain features that are described in this specification in the context of separate embodiments can also be implemented in combination in a single embodiment. Conversely, various features that are described in the context of a single embodiment can also be implemented in multiple embodiments separately or in any suitable subcombination. Moreover, although features may be described herein as acting in certain combinations and even initially claimed as such, one or more features from a claimed combination can in some cases be excised from the combination, and the claimed combination may be directed to a subcombination or variation of a subcombination.

Similarly, while operations are depicted in the drawings in a particular order, this should not be understood as requiring that such operations be performed in the particular order shown or in sequential order, or that all illustrated operations be performed, to achieve desirable results. In certain circumstances, multitasking and parallel processing may be advantageous. Moreover, the separation of various system modules and components in the embodiments described herein should not be understood as requiring such separation

in all embodiments, and it should be understood that the described program components and systems can generally be integrated together in a single product or packaged into multiple products.

5 Particular embodiments of the subject matter have been described. Other embodiments are within the scope of the following claims. For example, the actions recited in the claims can be performed in a different order and still achieve desirable results. As one example, the processes depicted in 10 the accompanying FIGURES do not necessarily require the particular order shown, or sequential order, to achieve desirable results.

What is claimed is:

1. A surgical gown for holding surgical instruments, the surgical gown comprising:

a first elongated pocket with first pocket edges, the first pocket edges include a first pocket right side edge and a first pocket left side edge, a first pocket bottom edge and a first pocket opening that extends along a width of the first elongated pocket, wherein the first pocket left side edge extends along an entire length of the first elongated pocket from the first pocket opening to the first pocket bottom edge;

a second elongated pocket with second pocket edges separate from the first pocket edges, wherein the second pocket edges include a second pocket right side edge and a second pocket left side edge that extends along a length of the second elongated pocket and are angled relative to the first pocket right side edge and the first pocket left side edge, and a second pocket bottom edge and a second pocket opening that extends along the width of the second elongated pocket; and

a base material, wherein the first elongated pocket is connected to the surgical gown via a first portion of the base material,

wherein the second elongated pocket is connected to the surgical gown via a second portion of the base material, and

wherein the first elongated pocket, and the second elongated pocket are permanently connected to the surgical gown with the first pocket opening and the second pocket opening at an upper torso area of the surgical gown, are arranged in a fixed configuration in relation to one another, and are configured to releasably hold instruments.

2. The surgical gown of claim 1, wherein the first elongated pocket has a length longer than the width of the first elongated pocket, and the second elongated pocket has a length longer than the width of the second elongated pocket.

3. The surgical gown of claim 2, wherein a first portion of the base material extends directly from the first pocket opening of the first elongated pocket.

4. The surgical gown of claim 3, wherein a second portion of the base material extends directly from the second pocket opening of the second elongated pocket.

5. The surgical gown of claim 1, further comprising a loop between the first elongated pocket and the second elongated pocket.

6. The surgical gown of claim 1, further comprising a first gown portion above a second gown portion, wherein the first gown portion is configured to be worn above a waist area of a user and the second gown portion is configured to be worn below the waist area of the user, wherein the first elongated pocket and the second elongated pocket are on the first gown portion.

7. The surgical gown of claim 6, further comprising a loop between the first elongated pocket and the second elongated

pocket, wherein the loop is permanently connected to the first gown portion and arranged in a fixed configuration in relation to the first elongated pocket and the second elongated pocket.

8. The surgical gown of claim 1, wherein the base material includes an adhesive by which the base material is permanently connected to the surgical gown.

9. The surgical gown of claim 1, wherein the first elongated pocket and second elongated pocket are located at a bodice of the surgical gown.

10. A gown for use in a surgical environment, the gown comprising:

a base material;

a first elongated pocket with a first pocket opening at an upper torso area of the gown with three first pocket borders including a first pocket right side border and a first pocket left side border that extend along an entire length of the first elongated pocket;

a second elongated pocket with three second pocket borders that are separate from the three first pocket borders of the first elongated pocket, wherein the three second pocket borders include a second pocket right side border and a second pocket left side border that extend along an entire length of the second elongated pocket and are angled relative to the first pocket right side border and the first pocket left side border; and one or more loops between the first elongated pocket and the second elongated pocket, wherein the first elongated pocket is connected to the gown via a first portion of the base material,

wherein the second elongated pocket is connected to the gown via a second portion of the base material, and wherein the one or more loops, the first elongated pocket, and the second elongated pocket are each configured to hold instruments and are permanently connected to the gown.

11. The gown of claim 10, wherein the first portion of the base material extends from the first pocket opening of the first elongated pocket.

12. The gown of claim 11, wherein the second portion of the base material extends from a second pocket opening of the second elongated pocket.

13. The gown of claim 10, wherein the second elongated pocket is attached to a chest area of the gown.

14. The gown of claim 10, further comprising a first gown portion and a second gown portion, wherein the first gown portion is configured to be worn at the upper torso area of a

user and the second gown portion is configured to be worn below the upper torso area of the user, wherein the first pocket opening of the first elongated pocket and a second pocket opening of the second elongated pocket are at the first gown portion.

15. The gown of claim 10, further comprising a sleeve loop attached to a sleeve of the gown.

16. A surgical gown comprising:

a first portion configured to be worn at a front upper torso area of a user;

a second portion configured to be worn below the upper torso area of the user, the first portion comprising a base material;

a first pocket with first pocket borders, the first pocket borders comprising a first pocket right side border and a first pocket left side border that extend along an entire length of the first pocket, and a first pocket bottom border; and

a second pocket with second pocket borders separate from the first pocket borders, wherein the second pocket borders comprises a second pocket right side border and a second pocket left side border that extend along an entire length of the second pocket, and a second pocket bottom border,

wherein the first pocket and the second pocket have openings at the first portion of the surgical gown and the first pocket right side border and first pocket left side border are arranged at a non-zero angle relative to the second pocket right side border and the second pocket left side border, and

wherein the first pocket and the second pocket are permanently connected to an outside facing surface of the surgical gown via the base material.

17. The surgical gown of claim 16, further comprising one or more loops connected to one of the second portion of the surgical gown or a sleeve of the surgical gown.

18. The surgical gown of claim 16, wherein the first and second pocket each comprise a top section and a bottom section, wherein the bottom sections of the first pocket and the second pocket are permanently connected to the outside facing surface of the surgical gown via the base material.

19. The surgical gown of claim 16, wherein the base material is formed of a single piece of material.

20. The surgical gown of claim 16, wherein the first pocket and the second pocket are substantially symmetrical with respect to a vertical center-line of the gown.
